Design No 417. Lyman Cobb Design for Stoves Patented Oct. 14. 1851.

Burridge Clerical Co.

Des. 417

Lyman Cobb, of Akron, Ohio
Letters Patent, No. 417. Dated Oct. 14, 1851

The schedule referred to in these Letters Patent & making part of the same.

To all whom it may concern:

Be it known that I, S. Cobb
of Akron, in the county of Summit and state of Ohio, have invented
& produced a new & useful design for the front of hearth plates
of a Franklin Stove of the kind usually denominated, the Franklin
Stove: and I do hereby declare that the following is a full and
exact description thereof, reference being had to the accom-
panying drawing, in which my ornamental design is clearly
represented.

The shape & configuration of the

plates is designated by the general outline of the drawings; the ornament on the upper portion or breast of the front plate A, consists of the scroll work leafing B, B, & C.

Its sides or jambs have on them the ornamental leafing shown at D, D, & on the lower portion are the vases E, E, containing bouquets. The vases rest upon the scroll work at the base of the jambs F, F. - The ornamental work on the front plate A, being in low relief.

The ornaments on the hearth plate G, are shown by the work leafing H, forming an ornamental border around the hearth plate. Each corner is ornamented with scroll work, corresponding in form and configuration to the corners I, I. On the front edge or border of the hearth, is the scroll work, as shown at J. -

Having thus distinctly represented & described the nature & arrangement of the respective ornaments & figures upon the front & hearth plates of my Franklin Stove, What I claim therein as new & desire to secure by Letters Patent, is the design, configuration and arrangement of the said ornaments as herein designated and represented.
